CLAIM

I claim the ornamental design for an apron with removable potholders, as shown and described.

DESCRIPTION

FIG. 1 is a reduced front perspective view of an apron with removable potholders showing my new design in use;

FIG. 2 is a front perspective view thereof;

FIG. 3 is another front perspective view thereof;

FIG. 4 is a rear view thereof, showing the apron's straps in an alternate position;

FIG. 5 is a front view thereof, showing the apron's straps in an alternate position; and,

FIG. 6 is an exploded front perspective view thereof, showing the potholders separated from the apron.

The broken line shown in FIG. 1 is included for the purpose of illustrating environmental structure and forms no part of the claimed design.
